UNITED STATES PATENT OFFICE.

CHARLES A. RANDALL, OF NEW YORK, N. Y.

ELECTRO-MAGNETIC RELAY.

SPECIFICATION forming part of Letters Patent No. 254,045, dated February 21, 1882.

Application filed April 5, 1880. (No model.)

To all whom it may concern:

Be it known that I, CHARLES A. RANDALL, a citizen of the United States, residing at New York, in the county of New York and State of New York, have invented new and useful Improvements in Electro-Magnetic Relays, of which the following is a specification.

This invention relates to that class of telegraphic instruments technically named "relays," which are included in main-line circuits and arranged to control the flow of battery-currents over local circuits.

As heretofore constructed a relay has generally consisted of an electro-magnet having its armature secured to a lever on a rock-shaft mounted in suitable bearings, a vibratory movement of said lever being caused by the attraction of the armature by the magnet and the retractile force of an adjustable spring acting alternately. The movement of the lever is usually limited by one or more adjustable stop-screws, one of said screws serving as a contact terminal of an electric circuit of which the vibratory lever is the other terminal, so that by the vibration of said lever the circuit is alternately made and broken.

The object of my invention is to simplify the construction of relays and obviate the trouble and loss of time occasioned by the frequent necessity for adjustment of the stop-screws and retractile spring of the armature-lever.

To this end it consists in, first, the combination, in an electro-magnetic relay, of the elastic or spring arm constituting one terminal of the apparatus, the carbon or other suitable button constituting the other terminal, and with which the elastic arm is in permanent contact, an electro-magnet the attraction of which draws the elastic arm against the carbon button, and suitable electrical connections whereby the terminals may be held in contact with a varying force and the current correspondingly varied, the spring-arm affording the proper elasticity of contact, as hereinafter set forth; second, the combination, in an electro-magnetic relay, of the elastic or yielding lever, a suitable fixed terminal or button in permanent contact with the lever, an electro-magnet which draws the lever against the fixed terminal, and a screw for adjusting the magnet, as hereinafter set forth.

In the accompanying drawings, Figure 1 is

a side elevation of a tension-changing relay constructed according to my invention, and Fig. 2 a perspective view of the same.

The letter A designates an electro-magnet, to the cross-bar of which is secured a screw-rod, B, passing loosely through an aperture in a bracket, C, and having upon its outer portion a thumb-nut, D. Between the bracket and the cross-bar of the armature the screw-rod B is surrounded by a spiral spring, E, the ends of which bear against said bracket and cross-bar, respectively. By means of the screw-rod, when the nut is screwed inwardly upon it, the magnet is drawn away from the armature F, and by means of the spring E, when the nut is screwed outwardly, the magnet is moved toward said armature, so that the force with which the magnet acts upon its armature may be controlled as desired, or the distance through which the magnetic influence of the core acts upon said armature may be regulated in accordance with the strength of the current which may be passing over the coils of the magnet. The armature F is secured to an elastic metallic lever, G, projecting from a metallic arbor, h, mounted in bearings in the metallic studs i. The top or free end of the elastic lever G rests permanently but loosely against a carbon button, K, supported by a post, l, and said carbon button forms one terminal of an electric circuit, (usually a local circuit at a telegraph-office,) the elastic lever being the other terminal and connected with the battery through its arbor and the bearings thereof and a suitable wire. The electro-magnet is included in the main or line wire circuit, and when the strength of the current upon said main circuit is varied by any suitable means the action of the magnet upon its armature causes corresponding vibrations of the pressure with which the elastic lever bears upon the carbon button. The main circuit should be constantly closed, but so regulated that normally the pressure between said button and lever will be very slight, and consequently but a very light current will flow over the local circuit, not sufficient to produce any mechanical operation of instruments included in said local circuit; but when the strength of the current upon the main circuit is increased and the pressure between the elastic lever and carbon button increased correspondingly the current of the local battery

flows freely over its circuit in such quantity as to operate the included local instruments, the increase and decrease of pressure thus resulting in the same effect which is produced by the makes and breaks of the ordinary relay.

I am aware that heretofore a relay in which the current has been varied by varying the resistances by pressure of a substance interposed between the terminals of the relay has 10 been shown and described; but the organization of apparatus thus described is practically defective and is different from that claimed herein.

What I claim is—

15 1. The combination, in an electro-magnetic relay, of the elastic or spring arm constituting one terminal of the apparatus, the carbon or other suitable button constituting the other terminal, and with which the elastic arm is in permanent contact, an electro-magnet the attraction of which draws the elastic arm against the

carbon button, and suitable electrical connections whereby the terminals may be held in contact with a varying force and the current correspondingly varied, the spring-arm affording the proper elasticity of contact, substantially as and for the purpose set forth.

2. The combination, in an electro-magnetic relay, of the elastic or yielding lever, a suitable fixed terminal or button in permanent contact with the lever, an electro-magnet which draws the lever against the fixed terminal, and a screw for adjusting the magnet, substantially as and for the purpose set forth.

In testimony whereof I have hereunto set my hand in the presence of two subscribing witnesses.

CHARLES A. RANDALL.
